(57) **CLAIM**

The ornamental design for a retractable and foldable drying rack as shown and described.

DESCRIPTION

FIG. 1 is a front, top, and left perspective view thereof; FIG. 2 is a rear, bottom, and left perspective view thereof; FIG. 3 is a front view thereof; FIG. 4 is a rear view thereof; FIG. 5 is a left side view thereof; FIG. 6 is a right side view thereof; FIG. 7 is a top view thereof; and FIG. 8 is a bottom view thereof. FIG. 9 is front, top, and right perspective view showing an expanded state thereof; and, FIG. 10 is rear, bottom, and left perspective view showing an expanded state thereof. The figures are illustrated to show contrasting appearance. Areas of the retractable and foldable drying rack that appear in different shades of gray represent areas with contrasting appearances only and do not represent any particular color, material, texture or finish. The broken lines in the figures illustrate portions of the retractable and foldable drying rack that form no part of the design.
